(57) **CLAIM**

The ornamental design for a computer having graphical user interface, as shown and described.

DESCRIPTION

This Design Application is also related to co-pending U.S. Design patent application Ser. No. 29/438,013, filed on Nov. 25, 2012, entitled Computer Having Graphical User Interface; U.S. Design patent application Ser. No. 29/438,014, filed on Nov. 25, 2012, entitled Computer Having Graphical User Interface; and U.S. Design patent application Ser. No. 29/438,015, filed on Nov. 25, 2012, entitled Computer Having Graphical User Interface. The disclosures of these Design Applications are considered part of and are incorporated by reference in the disclosure of this Design Application

FIG. 1 is a perspective view illustrating a computer having graphical user interface according to the present design; and, FIG. 2 is a front view thereof.

The computer shown in broken lines forms no part of the claimed design.
